[57] CLAIM

The ornamental design for a body mounted lamp, as shown and described.

DESCRIPTION

FIG. 1 is a top, front isometric view of a body mounted lamp showing my new design;

FIG. 2 is a front elevational view thereof;

FIG. 3 is a rear elevational view thereof;

FIG. 4 is a top plan view thereof;

FIG. 5 is a side elevational view thereof, the opposite being a mirror image.

The bottom is flat and unornamented.
